WHEEL FLANGE LUBRICATOR

Filed June 21, 1927

UNITED STATES PATENT OFFICE

LESTER J. RICKARD, OF UMATILLA, OREGON

WHEEL-FLANGE LUBRICATOR

Application filed June 21, 1927. Serial No. 200,388.

My invention relates to improvements in flange lubricators for wheels, and more particularly to lubricators using grease in stick form designed to lubricate the flanges of 5 railway cars, locomotives, street railway cars and other vehicles running on rails.

The invention has for an object to provide an extremely simple and economical device which may be readily applied to the vehicle 10 and may be easily and quickly replenished, and by which the lubricant will be constantly applied to the wheel flange with an even pressure.

A further object is to provide a flange lubricator which will thoroughly and constantly lubricate the flanges of the wheels of a locomotive or car, especially when the wheels are traveling on the curved portions of a track, as very little, if any, lubrication of the flange 20 is necessary when the wheels are traveling on a straight track.

A further object of the invention is to provide a lubricator for the flanges of the wheels which will automatically feed the lubricant 25 directly on the flange of the wheel in such a manner as to prevent the same from flowing or slopping onto the tread of the wheel, which would tend to lessen its tractive power.

A further object of the invention is to provide 30 a device which affords convenience in the application of the lubricant stick for use and removal of the operating parts for cleaning, repairs, etc.

A further object is to provide a lubricant 35 stick put up in a wrapper which preserves the integrity of the lubricant, and which wrapper must be worn off as the stick feeds out to the flange.

With these and other objects in view the invention consists in the novel features of construction and arrangement and combination of parts hereinafter explained and particularly defined in the appended claims.

The invention is illustrated in the accompanying drawing showing the lubricator applied to a locomotive, and in which—

Figure 1 is a fragmentary side view of a locomotive showing the device applied to act 50 on a drive wheel of the locomotive;

Figure 2 is a longitudinal section through the lubricator proper;

Figure 3 is a side elevation of the device as applied;

Figure 4 is a transverse section as on line 4—4 of Figure 3;

Figure 5 is a perspective view of the lubricant stick with the wrapper;

Figure 6 is a transverse section through the stick and wrapper.

A cylindrical casing 10 formed preferably of metal open at both ends with an internal shoulder 11 at its front end and a thimble 12 screwed on its opposite end, is adapted to be fixedly but adjustably secured in operative 65 position on a locomotive by a bracket B, which is itself secured to the locomotive by suitable bolts and nuts N the connection between the bracket and casing being made by means of suitable clamps C.

Fitting within the case 10 to reciprocate longitudinally therethrough and through the perforated thimble 12, is a pipe or tube 13 provided at a suitable distance from the lower end with a collar 14, which is adapted to 75 contact with the internal shoulder 11 to limit its movement in one direction induced by the spring 15 which surrounds the pipe 13, within the casing 10 one end of said spring abutting the collar 14 and the upper end abutting a collar 16 held in place within the tube 10 by the nipple or thimble 12.

The lower end of the pipe or tube 13 is provided with a threaded annular shoe 17 which is adapted to be forced by the spring 85 15 to fit the throat flange of the wheel, it being beveled or rounded off as at 17^a, which protects the lubricant from dust and rain.

Connected to the upper end of tube 13 by a short coupling nipple 18 is a short tube 19 90 to the outer end of which is removably applied, as by screw threads, the cap 20; this cap is perforated centrally, and suspended therefrom is a suitable bracket 21, having attached thereto a chain 22 carrying at its lower end a follower weight 23 adapted to bear on the stick of lubricant 24 with a constant pressure as the stick feeds to the throat of wheel flange; the bracket 21 is removably held in the cap 20 by a bolt and nut 26.

The lubricant stick 27 is of the hard grease variety and is wrapped in paper comprising several layers or convolutions 28 in which way it is fed to the flange, the paper wrapper serving to prevent sticking in the tube, or wearing down in the same.

The grease stick is applied by unscrewing the short upper section 19 and inserting the stick of grease in the tube 18, the weight 23 holding the grease stick against the flange of the locomotive wheel.

The amount of grease used is regulated by the amount of paper that is wrapped around it, as it must wear off the paper on the stick to get the grease on the flange.

It is apparent that the device may simply comprise the grease tube, with its shoe and collar, the spring, the casing with its internal shoulder 11, and the follower weight but it is advisable to use the nipples, joints and cap 20, for convenience and ease of cleaning and replacing of parts.

An advantage in the present device and the stick of grease is that when a train is stopped the grease does not flow down on the wheel like oil does and consequently a puddle does not collect which would render the starting of the train very difficult.

From the above it will be seen that I provide a lubricator of few parts and one that feeds hard grease, or substantially solid lubrication by a shoe yieldingly held to the throat of the flange of the wheel to accommodate itself to any and all movements thereof, the amount of grease used being regulated by the amount of paper that is wrapped around it.

It is suggested that in the maintenance of the device, that after each trip that the spring pressed tube be pulled back and the end looked at to see that the grease is down on the flange; if so the device is in proper working order: if not, unscrew the nipple out of the end and push a small rod in the grease and pull it out. Then take the other end of this rod which may be flattened out and clean out the pipe down by the shoe as dirt accumulates there and does not allow the grease to feed freely.

When filling do not force the grease in the pipe as such action may burst the paper and the grease will stick to the pipe. Do not fill it full but leave about two inches at the top giving room for the weight and chain to join without crushing the tube. Add a piece of grease after each trip.

It is of course obvious that this device may be fastened to the frame or any other suitable part of locomotives and street cars or the like.

Having thus fully described my invention, what I claim:

1. A wheel flange lubricating device comprising in combination, a tubular supporting casing open at its opposite ends and having an inner annular shoulder at its lower end, a lubricant carrying tube freely slid-

able through said supporting casing and provided intermediate its ends, with a stop collar adapted to coact with the said annular shoulder to limit the outer movement of the lubricant tube, an annular shoe at the lower end of the lubricant tube, the upper end of said lubricant carrying tube provided with a removable closure cap coiled spring means surrounding the lubricant carrying tube for controlling the movement of the same, a lubricant pencil having a paper jacket enclosing the same, freely slidable in said lubricant carrying tube, the paper jacket preserving the integrity of the lubricant and preventing sticking in the tube, a sliding weight follower in constant engagement with the upper end of said lubricant pencil, and flexible means connecting said follower with the closure cap.

2. A wheel flange lubricating device comprising in combination a tubular casing adjustably supported on a vehicle, said casing open at its upper and lower ends, an internal annular shoulder at its lower end and a removable perforated thimble at its upper end, a lubricant carrying tube mounted in said casing and reciprocable through the thimble and lower end of the casing, a collar on said tube adjacent its lower end and adapted to contact with the annular shoulder to limit the outer movement of said tube in said casing, a collar on said tube adjacent its upper end and adjacent the perforated thimble, a spring surrounding said lubricant carrying tube and bearing at its opposite ends against said collars respectively, a second tubular section detachably connected with the upper end of the lubricant carrying tube and in alignment therewith, a removable cap closing the upper end of said second tube, a lubricant pencil slidably mounted in the first named tube, a weight follower flexibly suspended from said cover and movable in the lubricant carrying tube, said weight adapted to rest upon the lubricant pencil and urge the opposite end thereof from said tube.

3. In a wheel flange lubricating device, the combination with a guide casing adapted to be adjustably supported obliquely with respect to the flange of a car wheel, a spring pressed tube having its upper end closed, an adjustable annular shoe at the lower end of said tube, the lower end of said shoe being bevelled and adapted to be positioned adjacent the throat of the wheel flange, a lubricant pencil mounted in said tube, and means freely slidably in said tube and bearing on said lubricant pencil and urging the same through said shoe whereby to lubricate the throat of the wheel flange.

LESTER J. RICKARD.
